(57) **CLAIM**

The ornamental design for a portion of a keyboard, as shown and described.

DESCRIPTION

FIG. 1 is a perspective view of a portion of a keyboard showing our new design;

FIG. 2 is a top view thereof;

FIG. 3 is a front view thereof;

FIG. 4 is a left side view thereof;

FIG. 5 is a right side view thereof;

FIG. 6 is a back view thereof; and,

FIG. 7 is a bottom view thereof.

The broken line showing of the key edges and the remainder of the keyboard is for illustrative purposes only and forms no part of the claimed design.

1 Claim, 6 Drawing Sheets
